Patented June 26, 1917.

Inventor

Louis Desrochers
By Joseph A. Miller
Attorney

UNITED STATES PATENT OFFICE.

LOUIS DESROCHERS, OF FALL RIVER, MASSACHUSETTS, ASSIGNOR OF ONE-HALF TO
SAMUEL F. STEWART, OF NORTH TIVERTON, RHODE ISLAND.

HANDSAW.

1,231,338.

Specification c^o Letters Patent. Patented June 26, 1917.

Application filed January 26, 1917. Serial No. 144,754.

To all whom it may concern:

Be it known that I, LOUIS DESROCHERS, a citizen of the United States, residing at Fall River, in the county of Bristol and State 5 of Massachusetts, have invented a new and useful Improvement in Handsaws, of which the following is a specification.

This invention relates to certain new and useful improvements in hand saws, and relates more particularly to means associated 10 with the handle thereof to enable the easy and accurate marking of material or the like to be cut, or for any other purpose, which markings may be at right or other angles.

15 Further, the invention aims to provide improved means for enabling the front or rear ends of the handle of the saw to be used for marking purposes, and to also provide a simple and easily operated attachment for allowing the marking of acute or obtuse angles.

Other and further objects will be later hereinafter set forth and manifested in the course of the following description.

25 In the drawings—

Figure 1 is a fragmentary side elevation of a saw with the handle thereof shown partly broken away and in section and having the present invention applied thereto.

30 Fig. 2 is a top plan edge view.

Fig. 3 is an enlarged section on line 3—3 of Fig. 1.

Fig. 4 is a section on the line 4—4 of Fig. 3, and

35 Fig. 5 is a detail perspective view of the front wear points.

In proceeding in accordance with the present invention the handle 1 attached to the usual saw blade 2 is formed with a lateral 40 passage chamber or opening 3, which at its outer end terminates in a lateral extension or part 4. A plate 5 is rigidly secured to the top side edge of the handle and has an extension 6, which conformably fits in the 45 part 4. The plate 5 is formed with an opening 7 in register with the chamber 3, and has hinged at 8 to its inner end an arm 9 which is used in cutting or marking bevels. The arm 9 is provided with a link 10 hinged 50 thereto at 11 and operating in the chamber 3 and having teeth 12 to form a positive engagement with the plate 5 adjacent its opening 7, a thumb screw 13 being threaded through the extension 6 of plate 5, and at 55 its free end bearing against link 10, so as to

hold the latter locked in any position to which it may be moved, as depicted in Fig. 1.

From the foregoing, it will be readily apparent that by setting or adjusting the arm 9, in desired angular relation to the edge E 60 of the saw the arm 9 may be used in marking bevels, or angles by using same in conjunction with the edge E.

The outer tips T of the saw handle are provided with transverse grooves in which 65 the legs of T-shaped wear points or members 14 are received, these members being in a line drawn at direct right angles to the edge E of the saw blade.

70 Wear points or members 15 are also provided in the inner tips 1 of the handle, these tips having cut-away parts or end shoulders 16 engaged by the heads 17 of the screw fastenings so as to clamp the wear points in position, thus eliminating the necessity of the separate fastenings in the case 75 of the members 14, which latter fastening means consists of screws 18, as shown in dotted lines Fig. 2.

The handle is also provided with levels 80 20 and 21, arranged at right angles.

From the foregoing it will be apparent that the wearing points or members at the opposite ends of the handle may be used to obtain right angular lines, for instance if a 85 line is desired at right angles to the dotted line X the points 14 are placed against the surface X and a line is then drawn along the edge E of the saw blade. Similarly the points 15 can be placed against a line or surface Y and a line drawn along the same edge E of the saw blade.

90 The saw is thus capable of various uses as will be apparent from the foregoing taken in connection with the drawings.

95 Having thus described my invention, what I claim as new and desire to secure by Letters Patent is—

1. A saw having a handle, said handle having its inner end points formed with 100 slots, wear members in said slots having end shoulders disposed interiorly of the outer side faces of the handle, and fastening means for the blade having heads which abut the shoulders and clamp the wear 105 members in position.

2. A saw having a handle, fastening means for the saw blade, said handle having spaced transverse slots extending through the front edge of the handle opposite to said fasten- 110

ing means, and wear members arranged in said slots and engaged with said fastening means so as to be held in the slots thereby.

3. A saw having a handle, fastening means for the saw blade having heads, said handle having spaced transverse slots extending through the front edge of the handle opposite to said fastening means, and wear members arranged in the slots and engaged 10 with the heads of the fastening means so as to be held in the slots thereby.
4. A saw having a handle formed with spaced points which project inwardly

toward the saw blade, members extending transversely of the points and having end parts, and fastening means for the saw blade having heads which abut the end parts of the members and clamp same therebetween.

In testimony whereof I have signed my name to this specification in the presence of 20 two subscribing witnesses.

LOUIS DESROCHERS.
